UNITED STATES PATENT OFFICE

MARSHALL K. McCOSH, OF REISTERSTOWN, MARYLAND

PARTITION AND WALL

Application filed October 19, 1932. Serial No. 638,628.

This invention relates to partitions and walls adjustable to furniture drawers, rooms and other situations of different widths and lengths.

The objects of the invention are to provide a partition the length of which can easily be fitted to drawers and rooms of different lengths or widths; that is simple of construction and of low cost; that can be made of very thin or thicker sheet metal or other material that possesses the property of being stiff and withal capable of being bent through at least ninety degrees, that can be fairly easily and accurately bent to the length and shape to fit in place and yet be reasonably firm, after installation, in the position in which it is installed; and that can easily and cheaply be packed, shipped and handled.

Other objects will appear from the following description. Novel construction and combinations are described, illustrated, and specifically set forth in the claims.

In the accompanying drawing—

Figure 1 is a perspective of what seems to me now to be the preferred embodiment of my invention for use as a drawer partition. It indicates, also, in dot-and-dash lines a dull-edge tool in position to form an indentation near the rear end of the device preparatory to bending the device to a right angle at the indentation.

Figure 2 shows two perspectives of the device after being bent in the operation of installation in a drawer. The perspective at the forward end of the drawer shows the forward end of the device bent to a right angle at the indentation 5 shown in Figure 1, and the device being in position to have its rear end marked where it is to be bent to a right angle to fit in the drawer as shown by the perspective appearing at the rear of the drawer. The latter-mentioned perspective shows the device after it has been bent at both ends and positioned in the drawer preparatory to its being fixed in that position by tacks or nails: it shows, also, the free end of cleat B bent parallel with the bottom of the drawer preparatory to being fixed thereto by a tack or nail.

Figure 3 is a cross-section of the device

after installation, on the line 3—3 of Figure 2.

Figure 4 is a detail perspective of the rear end of the device after it has been bent to a right angle in the operation of installation as shown in the perspective appearing at the rear of the drawer of Figure 2.

The device, shown in Figure 1, is made of two pieces of thin sheet metal, one piece being the body A and the other piece the cleat B. The body A is folded twice at its two side-edges, forming folds 1 and 2, each of the folds consisting of three thicknesses of the metal, both to strengthen the body and so there will be no very sharp edges of metal to damage objects coming in contact with the device after it is installed. Cross-sections of these folds 1 and 2 are shown in detail in Figure 3, the cross-section of fold 2 showing the cleat B included therein. The body A is also folded once at its two end-edges, forming folds 3 and 4 as shown in Figures 1, 2 and 4. In making the body A, folds 1 and 2 are formed first and then the folds 3 and 4 are formed. Except at the folds 1, 2, 3 and 4, the body A is of one thickness of metal. Cleat B, also, is folded at its side edges and its free end edge so that there will be no sharp edges exposed; but for the sake of simplicity the drawing does not show these folds.

Adjacent to the fold 3, which is at the forward end of the body A, and parallel thereto, is an indentation 5 in the body A and across its width. Between this indentation 5 and the forward end-edge of the body A are two holes 6 and 7 extending through the six thicknesses of metal. At the rear end of body A are two series of holes, series 8 to 13, inclusive, and series 14 to 19, inclusive, extending through the folds 1 and 2, respectively, the holes 8 and 14 being the ones nearest the rear edge of the body A and extending through the six thicknesses of metal. Each hole of series 8 to 13, inclusive, is directly opposite a hole of the series 14 to 19, inclusive, that is; a line drawn through the center of each of the holes of series 8 to 13, inclusive, and perpendicular to the side edges of body A would pass through the center of a hole of series 14 to 19, inclusive. One end of the cleat B is folded in with the fold 2, about midway of

the length of said fold 2, thereby being fixed to fold 2. The free end 20 of the cleat B is bent over fold 2 to extend to the adjacent side edge of the body A and then bent back upon 5 itself on a line as nearly as possible identical with the said side edge of body A, which line is designated at 21. A hole 22 extends through the cleat B near the end-edge of its free end 20.

10 The device is used by installing it in a drawing or similar place as follows: The forward end of the body A is first bent to a right angle on the line of the indentation 5. A person can do the bending fairly easily and 15 accurately by placing the device on a box or board so that the line of the indentation 5 is directly over the edge of the box or board and pressing or striking the forward end of the folds downward until it is bent to a right 20 angle with the indentation 5 becoming the inner corner of the right angle. Then the device is held across the top of a drawer 25 as shown by the perspective at the forward end of the drawer 25 of Figure 2 and a mark 25 is made on the body A at the edge adjacent to the drawer and on the side of the body that is shown uppermost in Figure 1 to indicate where it is to be bent at right angles to fit in the drawer at the desired position. Then a 30 mark is made in a similar manner at the opposite edge of the body, and a line drawn across the body joining these two marks. A dull-edge tool 23 such as indicated by the dot-and-dash lines of Figure 1 is then held with 35 its dull edge on the line drawn across the body A and the said tool 23 hammered so that it indents the body A on said line. The body A is then bent to a right angle along this indentation in a manner similar to the manner 40 in which the body A was bent along indentation 5, this second indentation becoming the inside corner 24 of the right angle bend. The device is then positioned in the drawer 25 as shown in the perspective at the rear of 45 the drawer in Figure 2 and the free end of the cleat B is bent at line 21 until the circular edge of the hole 22 lies parallel with the bottom of the drawer. Then the device is fixed in the desired position by tacks or nails driven 50 through holes 6 and 7, 8 and 14, 11 and 17, the holes 11 and 17 being the holes nearest the corner 24 through which tacks or nails can conveniently be driven into the drawer 25, and through hole 22.

55 The device can be made with the forward end of the body A bent to a right angle along the line of indentation 5 instead of simply indented. The advantage of its being simply indented is that it is easier and more economical to handle and ship. Also, the article can be manufactured with a series of indentations at the rear end of the body A, to simplify 60 the bending necessary to fitting the device in a drawer; in which case the person installing the device would not need to use a tool 23

to indent the body A. None of such indentations made in the body during manufacture may be found exactly at the most desired point by a person installing the device, in which case that person can bend the body to 70 some degree less than ninety degrees at each of several adjacent indentations and thus secure a satisfactory fit. Also, several cleats can be connected to the body when the device is made. The cleat or cleats hold the 75 installed device more firmly in position than it would be held without a cleat. The cleat or cleats can be movably connected to the body A in such a manner that it or they can be fastened to the drawer at any one of a 80 number of locations.

In case thicker sheet metal is used in making the device, the body A can be a flat piece of sheet metal having no folds at the edges, but having, instead, reenforcing strips affixed 85 thereto by welding or other means, and having an indentation 5 at the forward end of the body A and a series of indentations at the rear end of said body, series of holes 8 to 13, inclusive, and 14 to 19, inclusive, and a cleat 90 equivalent to cleat B welded or riveted to the body A. The indentations can be made either by a blow or pressure of a tool or by removing some of the metal along the line of indentation by machining or other means. The device made of the heavier sheet metal 95 can be installed in a drawer by the method described in the preceding paragraph. Instead of the cleat or cleats B being welded or riveted to the body, it or they can be movably connected to the body in such a manner that it or they can be fastened to the drawer at any one of a number of locations.

Folds such as shown in the drawing, reenforcing strips, or other reenforcing means, 105 may be on one side only of the device or on both sides. Reenforcing formations can be employed which extend from one side to the other, such, for instance, as a curl at the edges. When the device has the reenforcing means on one side only the indentations can 110 be made either on that side or on the other side, and the device bent either so that the reenforcing means are on the inside of the bend or on the outside; but usually the better results appear to follow when the bend is made with the reenforcing means on the outside of the bend. The indentations may be 115 made either at the reenforcing means only or in the entire width of the device; satisfactory results follow both methods, the bend being sharper, however, along its entire length when the indentation is in the entire width.

120 Other details of construction may be resorted to without departing from the spirit of the invention.

125 Where the device is to be used as a partition in a room of a building, or as a wall, a cleat or cleats may be connected with sev-

eral sides or edges of the body of the device in order that said cleat or cleats can be fastened to such objects as floors, ceilings, or other building members or attachments.

5 I claim:

1. A sheet metal partition comprising a relatively thin metal sheet having a pair of opposite side edges reenforced with one or more additional thicknesses of sheet metal 10 for providing lateral stiffness against bending, and a series of transversely aligned pairs of indentations formed across said reenforced side edges for facilitating the bending of said partition along a selected pair of indentations 15 in fitting the partition in place.

2. A sheet metal partition comprising a relatively thin metal sheet having a pair of opposite side edges reenforced with one or more additional thicknesses of sheet metal for providing lateral stiffness against bending, 70 a series of transversely aligned pairs of indentations formed across said reenforced side edges for facilitating the bending of said partition along a selected pair of indentations 75 in fitting the partition in place, and a fastening cleat adjustable along the reenforcing of one of said side edges.

MARSHALL K. McCOSH.
